UNITED STATES PATENT OFFICE.

WILLIAM A. WILLIS, OF PARSONS, KANSAS.

RAIL.

Application filed May 2, 1924. Serial No. 710,518.

To all whom it may concern:

Be it known that I, WILLIAM A. WILLIS, a citizen of the United States, residing at Parsons, in the county of Labette and State 5 of Kansas, have invented certain new and useful Improvements in Rails, of which the following is a specification, reference being had therein to the accompanying drawing.

My invention relates to new and useful 10 improvements in rails and has for its principal object the provision of a rail having a removable section, a depression being provided in the rail when the section is removed to allow the wheels of a locomotive 15 or the like to drop so as to transfer the weight from one wheel to another to allow the making of repairs such as removing and replacing springs, spring rigging, tires, brasses, or any other part of the locomotive.

20 A further object of the invention resides in forming the removable section by cutting out a portion of the rail tread and web, the web of the rail being thickened at the point where cut away and having openings 25 adjacent the ends of the cut out portion to receive projections formed on or secured to the cut out or removable section.

Another object consists in forming the upper surface of the web, where cut away, 30 with a concaved longitudinally extending recess to receive a longitudinally curved projection depending from the removable section.

With the above and other objects in view, 35 which will appear as the description proceeds, my invention consists in the novel details of construction, and arrangement of parts, described in the following specification and illustrated in the accompanying 40 drawings, and while I have illustrated and described the preferred embodiments of the invention, as they now appear to me, it will be understood that such changes may be made as will fall within the scope of the appended claims.

In the drawings:

Fig. 1 is a side elevation showing a section of a locomotive in position upon a rail.

Fig. 2 is a top plan of my improved rail 50 section.

Fig. 3 is a side elevation of my improved rail section with the removable portion raised.

Fig. 4 is a transverse vertical section on 55 the line 5—5 of Fig. 1, and

Fig. 5 is a transverse vertical section on the line 6—6 of Fig. 1.

In the drawings 1 indicates the base, 2 the tread and 3 the web of the rail, said web being thickened as shown at 4 for a purpose which will be later apparent. Longitudinally spaced openings 5 are formed in the web 3 for connecting the ends of adjacent rail sections in the usual manner. The tread 2 and the thickened portion 4 of the web 3 are cut away to provide the longitudinally curved recess 6 and the upper surface of the thickened portion 4 is flat, adjacent the ends of the cut out as shown at 7. Vertically extending openings 8 extend through the thickened portion 4 of the web, adjacent the ends of the cut out, the upper ends of said openings extending into the flattened portions 7 of the web. The ends of the tread 2, adjacent the cut out portion, are beveled as shown at 9. The cut out portion of the rail forms a removable section 10 which has the depending longitudinally curved projection 11 which is normally received in the longitudinally curved recess 6 and the upper end of this removable section forms a continuation of the tread 2 and the ends thereof are beveled as shown at 12. The depending portion 11 terminates short of the ends of the removable section and provides at the ends of the said section the longitudinally extending flat surfaces 13 which are adapted to be received upon the flat surfaces 7 of the web. Lugs or projections 14 extend downwardly from the flat surfaces 13 and are adapted to be received in the openings 8 of the web.

It will thus be seen that when the removable section 10 is in position relative to the rail that a continuous rail is provided and said removable section is held against transverse movement by means of the lugs or projections 14 being received in the openings 8. By beveling the ends of the tread as shown at 9 and the ends of the removable section as shown at 12 there will be no sharp corners at the meeting point of the removable section with the tread and there will be no jar or sudden impact when the wheels of the locomotive engage at these points.

Previous to my invention several methods have been used for removing and replacing springs, spring rigging, tires, brasses, etc., on locomotives. One of these methods consisted in using one or more heavy jacks and

another method consisted in running the proper wheel upon a wedge and then blocking the spring rigging and the engine frame at proper places. These and other methods have been found to take considerable time to do the necessary work, considerable expense is involved and often there is great danger to the one doing the repair work. With my improved construction of rail the work may be easily, quickly, and inexpensively done as the rail is so formed that it may be used, when desired, as a continuous rail for the operation of the locomotive thereover and then when it is desired to make the repairs the removable section may be taken from its normal position and by operating the locomotive in a manner which I will describe the repairs may be quite easily and quickly made. As an example of the manner in which the work may be done I have illustrated, in Fig. 1, one drive wheel and one trailer wheel of a locomotive with their connecting levers. The drive wheel is indicated at 15 and the trailer wheel at 16. When it is desired to remove the trailer spring 17 or the brasses indicated at 18 the locomotive will be positioned with the removable section between the drive wheel 15 and trailer wheel 16. The removable section is taken from its place, on both rails, and the engine is moved so that the driver wheels 15 will drop into the cut out portions of the rails. Normally these cut out portions will allow the wheels to drop approximately three inches causing considerable of the weight of the drive wheels to be transferred to the trailer wheels 16 through means of the equalizers 19, it being understood that the equalizers on opposite sides of the locomotive are connected by a cross equalizer 20 which passes through an opening formed in a connecting rod or bar 21 which is connected to one end of the equalizer 19 and one end of the driver spring 22. The opposite end of the equalizer 19 is connected to the trailer spring 17 by means of the connecting rod or bar 23. Each equalizer 19 is so positioned that the rear end is outside of the engine frame while the front end is on the inside between the two engine frames. The front end of the equalizer 19 is connected to a cross equalizer 20 by means of the long hanger 21, there being two of these hangers in between the engine frames one connecting the equalizer 19 with the cross equalizer and the other connecting the cross equalizer with an equalizer 19 on the opposite side of the engine. The cross equalizer 20 in its extreme ends is connected to the rear end of its rear driving springs by means of short hangers 20', these being located directly over the engine frame while the long hangers are located near the center of the cross equalizer 20 in between the engine frames. When the drive wheel lowers into the recess it causes the end of the equalizer 19 adjacent thereto to be lowered and the opposite end is raised. To hold the slack which is now in the spring rigging a block is placed between the equalizer 19 and the locomotive frame at the point shown at 24 and a block is also placed under the engine frame, on top of the driving box 25 at the point 26. The locomotive is then moved forward so that the drive wheels 15 are moved from the cut-out portions and are received on the tread of the rail, this movement of the locomotive raising the same approximately three inches at this point. Or in other words somewhat higher than the trailer wheels 16. The trailer wheels will then pass into the recesses and drop approximately three inches and as the equalizers are blocked so that they cannot equalize all of the weight is transferred from the trailer wheels 16 to the driver wheels 15 and the trailer spring 17 is perfectly free and can be easily removed and replaced by disconnecting the hangers. To remove or replace the trailer brass 18 it is only necessary to raise the weight of the trailer frame and this can be done with a small jack. The operation for repairing or replacing the brasses or springs of the different wheels of the locomotive will be substantially the same as previously described and it is thought that a further detailed description of the manner of using is not necessary at this time. Suffice to say that it is only necessary to so position the locomotive with respect to the cut-out portion that the required wheels may drop and so operate the equalizers as to take the weight from those wheels on which there are parts to be replaced or repaired and transfer the same to adjacent wheels. After the necessary repairs have been made the removable section may be replaced and the locomotives may travel over the rails as usual. By having the sections of the cut-out portion or recess longitudinally curved the wheels of the locomotive may be properly guided in returning to the tread and the lugs or projections depending from the removable section, entering the openings in the thickened portion 4 of the tread 3 will prevent accidental displacement of said section. The rail is so strengthened, by the thickened web, at the point of the cut-out portion that there is sufficient material to prevent breakage of the rail.

Having fully described my invention what I claim as new and desire to secure by Letters Patent is:

1. A rail of the character described having a longitudinally curved recess formed intermediate its ends and a removable section adapted to be received in said recess. 125
2. A rail of the character described having a recess formed intermediate its ends, reinforcing means adjacent said recess, and a 130

removable section adapted to be received within the recess.

3. A rail of the character described having a longitudinally curved recess formed intermediate its ends, a removable section adapted to be received in said recess, and means for preventing displacement of the removable section relative to the rail.

4. A rail of the character described having a recess formed intermediate the ends and openings within the recess, a removable section adapted to be received within the recess, and projections carried by the removable section and adapted to be received in the openings.

5. A rail of the character described having a longitudinally curved recess intermediate the ends, and a removable section adapted to be received in said recess, the removable section being curved to conform to the curvature of the recess.

6. A rail of the character described having a longitudinally curved recess intermediate the ends, and a removable section adapted to be received within the recess, said

removable section having a longitudinally curved projection to conform to the curvature of the recess.

7. A rail of the character described having a longitudinally curved recess intermediate its ends, the web of the rail being thickened adjacent the recess and having vertically extending openings therein, a removable section adapted to be received within said recess, said removable section having a longitudinally curved projection to conform to the curvature of the recess and projections carried by the removable section and adapted to be received within the openings.

8. A rail adapted for use in repairing locomotives or the like having a normally level surface for supporting the wheels of the locomotive and a detachable section adapted to be removed to provide a recess over which the wheels may be positioned and allowed to be lowered.

In testimony whereof I hereunto affix my signature.

WILLIAM A. WILLIS.
